US00D628343S

(12) **United States Design Patent**
Eigenstetter

(10) **Patent No.:** **US D628,343 S**
(45) **Date of Patent:** **** Nov. 30, 2010**

(54) **INFRARED RADIATION DRYER**

(75) Inventor: **Bernd Eigenstetter**, München (DE)

(73) Assignee: **Wella Aktiengesellschaft**, Darmstadt (DE)

(**) Term: **14 Years**

(21) Appl. No.: **29/326,389**

(22) Filed: **Oct. 16, 2008**

(30) **Foreign Application Priority Data**

Apr. 17, 2008 (DE) 402008001908

(51) **LOC (9) Cl.** **28-03**

(52) **U.S. Cl.** **D28/19**

(58) **Field of Classification Search** D28/12-19;

34/96-101; 392/380-385; 219/222

See application file for complete search history.

(57) **CLAIM**

The ornamental design for an infrared radiation dryer, as shown and described.

DESCRIPTION

FIG. 1 is a right side elevational view of an infrared radiation dryer showing my new design;

FIG. 2 is a left side elevational view;

FIG. 3 is a top plan view;

FIG. 4 is a bottom plan view;

FIG. 5 is a front elevational view;

FIG. 6 is a rear elevational view; and,

FIG. 7 is a perspective view.

Note that any broken line illustration of environmental structure in the drawing is not part of the design sought to be patented.
